Patented Oct. 25, 1921.

Izidor Bernstein INVENTOR

BY
Jack Ordinary ATTORNEY

UNITED STATES PATENT OFFICE.

ISIDOAR BERNSTEIN, OF BROOKLYN, NEW YORK.

DESIGN FOR A FINGER-RING.

59,453.

Specification for Design.

Patented Oct. 25, 1921.

Application filed November 11, 1920. Serial No. 423,499. Term of patent 7 years.

To all whom it may concern:

Be it known that I, ISIDOAR BERNSTEIN, a citizen of the United States of America, residing at Brooklyn, in the county of Kings and State of New York, have invented a new, original, and ornamental Design for Finger-Rings, of which the following is a specification, reference being had to the accompanying drawing, forming part thereof.

The figure is an edge elevation of the finger ring showing my new design.

I claim:

The ornamental design for a finger ring as shown.

In testimony whereof I have affixed my signature in presence of two witnesses.

ISIDOAR BERNSTEIN.

Witnesses:

JOHN H. BURROUGHS,
C. S. JENNINGS.
